207,137

AIRCRAFT

Antonio Cernuda, 5112 Navarro Lane, Apt. A,
Houston, Tex. 77027

Filed Dec. 27, 1965, Ser. No. 335

Term of patent 14 years

(Cl. D71—1)

FIGURE 1 is a side elevational view of an aircraft showing my new design;

FIGURE 2 is a top plan view thereof;

FIGURE 3 is a front elevational view thereof; and

FIGURE 4 is a perspective view thereof.

The essential features of my new design reside in the features shown in full lines.

I claim:

The ornamental design for an aircraft, substantially as shown and described.
